CLAIM

The ornamental design for a pharmaceutical tablet, substantially as shown and described.

DESCRIPTION

FIG. 1 is a front elevational view of a pharmaceutical tablet of my new design;

FIG. 2 is a top plan view thereof;

FIG. 3 is a bottom plan view thereof;

FIG. 4 is a side elevation view thereof; and

FIG. 5 is a back elevation view of the pharmaceutical tablet shown in FIGS. 1-4.
